CALKED HORSESHOE

William Hartill, 60 Clifton Crescent,
Sheffield S94 BE, England

Filed Apr. 14, 1971, Ser. No. 134,121

Term of patent 14 years

Int. Cl. D30—99

U.S. Cl. D30—35

FIG. 3.

FIG. 2.

FIG. 1.

FIG. 4.

FIG. 5.

FIG. 1 is a bottom plan view of a calked horseshoe, showing my new design;

FIG. 2 is a top perspective view;

FIG. 3 is a bottom perspective view;

FIG. 4 is a fragmentary cross-sectional view, partly in elevation, taken on the line 4—4 in FIG. 1; and

FIG. 5 is a cross-sectional view, partly in elevation, taken on line 5—5 in FIG. 2.

I claim:

The ornamental design for a calked horseshoe, as shown.
